SATURABLE MAGNETIC CORE CONTROL
DEVICEFrederic P. Schwieg, Jr., Nahant, Mass., assignor
to General Electric Company, a corporation of
New York

Application July 9, 1952, Serial No. 297,878

6 Claims. (Cl. 317—136)

1

My invention relates to improvements in saturable magnetic core control devices of the type wherein a magnetic flux, termed the control flux, controls the amplitude and phase of an electric signal, which may in turn control a servomotor for adjusting to a null position a permanent magnet which provides a portion of the control flux.

In particular, my invention relates to improvements in that type of control device which comprises a magnetic core having two saturable parts through both of which simultaneously pass two magnetic fluxes, which may be called the excitation flux and the control flux respectively. These two fluxes simultaneously aid each other in one of the saturable parts, and oppose each other in the other saturable part, thus saturating these parts unequally to a degree which depends upon the magnitude of the control flux. In consequence of the unequal saturations, voltage is induced in a signal winding which is balanced with respect to equal fluxes in the two saturable parts.

In control devices of this type heretofore known, the excitation flux may be produced by passing alternating current through an excitation winding, and magnetic saturation occurs twice during each cycle of this excitation current. As a result, the induced voltage in the signal winding is largely at the second harmonic frequency of the excitation current. However, it is often desirable, for the control of servomotors or the like, to have the electric signal at the fundamental frequency of the excitation current. While magnetic control devices which produce a fundamental-frequency signal are well known, such as those which employ a bridge-type circuit, they are generally less stable with respect to zero drift, are more expensive to manufacture, or have other disadvantages.

A principal object of my invention is to provide an improved saturable magnetic core control device which supplies, to a servomotor for example, an electric signal at the fundamental frequency of the excitation current, yet has the simplicity, stability and economy of manufacture usually associated with devices of the second harmonic type. Other objects and advantages will appear as the description proceeds.

Briefly stated, in accordance with one aspect of my invention, I connect a half-wave rectifier in series with the excitation winding of my device, and thus pass pulsating direct current through the excitation winding. This produces a pulsating excitation flux which, in conjunction with the control flux, produces magnetic saturation in the core but once each cycle of the excitation current,

2

and induces voltage in the signal winding which is largely at the fundamental frequency of the excitation current.

My invention will be better understood from the following description taken in connection with the accompanying drawing, and its scope will be pointed out in the appended claims.

In the drawing, the single figure is a diagrammatic illustration of a preferred embodiment of my invention.

Referring to the drawing, a magnetic core member 1 has two saturable outer legs 2 and 3, and also has a center leg 4 having a gap therein as shown. An excitation winding consists of two series-connected balanced halves 5 and 6 wound upon legs 2 and 3 respectively. Alternating current connections 7 and a half-wave rectifier 8 are in series with the excitation winding, as shown, and provide therethrough a pulsating direct current which produces a pulsating magnetic flux, termed the excitation flux, in core member 1. The respective polarities of the excitation winding halves are such that the excitation flux flows downward through leg 2 and upward through leg 3 of the core.

A signal winding consists of two series-connected balanced halves 9 and 10 wound upon legs 2 and 3 respectively. Electrical connections 11, including a series reactor 12, are provided whereby an electric current of variable magnitude and direction, termed the control current, may be applied to the signal winding. In flowing through the signal winding, the control current produces a portion of a magnetic flux termed the control flux. Another portion of the control flux is produced in a manner hereinafter explained. The polarities of signal winding halves 9 and 10 are such that the magnetic flux produced by the control current flows in the same direction through legs 2 and 3, either upward or downward depending upon the direction of the control current.

A cylindrical, permanent magnet 13, magnetized transversely along a diametrical plane, as indicated by the reference letters N and S in the drawing, is located in the gap of center leg 4, as shown. Magnet 13 provides the other portion of the control flux. The angular position of the permanent magnet is adjustable as hereinafter explained. Assume that magnet 13 is adjusted so that its plane of magnetization is vertical. Flux from the magnet passes upward through center leg 4, and downward through outer legs 2 and 3, or the reverse, depending upon the position of the magnet. Now, assume that magnet 13 is adjusted

to have its plane of magnetization horizontal. No net flux from the magnet passes vertically through legs 2 and 3. Intermediate positions of magnet 13 provide intermediate values of flux through legs 2 and 3.

The total control flux is the algebraic sum of the portions provided by magnet 13 and the control current respectively. In operation, the position of the magnet is adjusted automatically to a null position, as hereinafter explained, at which that portion of the control flux provided by magnet 13 is equal and opposite to that portion of the control flux provided by the control current flowing through the signal winding. When so adjusted, each position of the permanent magnet corresponds to a unique value in magnitude and direction of the control current.

From the foregoing description, it will be appreciated that the excitation flux and the control flux are simultaneously in mutually aiding relation in one of the saturable legs, and in mutually subtractive relation in the other saturable leg. It will also be appreciated that the signal winding is in balanced relation to equal amounts of the pulsating excitation flux in the two saturable legs, so that, in the absence of control flux, the excitation flux induces equal but opposite alternating voltages in the two balanced halves 9 and 10 of the signal winding, and no net induced voltage occurs across the whole of the signal winding.

Magnetic saturation occurs in one or both of the saturable legs 2 and 3 at the peak values, once each cycle, of the pulsating excitation flux. In the absence of a net control flux, both saturable legs become equally saturated, so that equal amounts of pulsating flux pass through both legs, and no net induced voltage appears across the signal winding. However, in the presence of a control flux which aids the excitation flux in one saturable leg, while opposing it in the other, the two legs become unequally saturated, and in consequence, unequal amounts of pulsating flux pass through the two legs. This induces a larger voltage in one half of the signal winding than in the other half, and the difference between these induced voltages appears as an electric signal across the whole of the signal winding. Since saturation occurs but once during each excitation cycle, this signal voltage is largely at the same frequency, and is either 90° or 270° out of phase with the fundamental-frequency alternating component of the pulsating excitation current.

The phase relation between the induced signal and the excitation current depends upon whether leg 2 or leg 3 is the more highly saturated, and hence depends upon the direction of the control flux. Thus, each reversal in direction of the control flux is accompanied by a phase reversal of the alternating electric signal across the signal winding.

Magnet 13 is mechanically connected to a servomotor 14, by a shaft 15 for example. Operation of the servomotor adjusts the angular position in the magnet, and thus adjusts the magnitude and direction of a portion of the control flux. Servomotor 14 is of a well-known type having a field winding connected to terminals 16 and a control winding connected to terminals 17, and having a rotor connected to shaft 15 which is capable of rotation in either direction selectively, depending upon the phase relation of alternating currents supplied to the field winding and the control winding respectively. Suitable

speed-reducing gears between the rotor and shaft 15 may be contained within the servomotor housing. The two windings of the motor are supplied with alternating currents of the same frequency which are substantially in phase quadrature. Shaft 15 is rotated in one direction when the control winding current leads the field winding current, and is rotated in the opposite direction when the control winding current lags the field winding current. Thus, a phase reversal of the control winding current reverses the servomotor. When no current is supplied to the control winding, the servomotor stops.

Alternating current which is substantially in phase quadrature with the fundamental-frequency component of excitation current is supplied to the field winding of the servomotor through alternating current connections 18 and a series capacitor 19. Alternating current which is either in phase, or 180° out of phase, selectively, with the fundamental-frequency component of the excitation current is supplied to the control winding of the motor through alternating current connections 20. Connections 20 are connected across a parallel-resonant circuit which consist of an inductor 21 and a capacitor 22 connected in parallel and resonant to fundamental-frequency electric signals. This resonant circuit is connected, in series with a direct-current blocking capacitor 23, across the signal winding, as shown.

Assume that a control current is applied through connections 11 which produces a net control flux in saturable legs 2 and 3, and thus causes unequal degrees of magnetic saturation to occur in the two saturable legs. An electric signal appears across the signal winding, which causes alternating current to flow through the control winding of the servomotor. The servomotor then rotates shaft 15, and thereby adjusts the angular position of magnet 13 to change the magnitude or direction, or both, of that portion of the control flux produced by the permanent magnet. This adjustment continues until a null position is reached, at which that portion of the control flux produced by magnet 13 is equal and opposite to that portion of the control flux produced by the control current. The signal voltage then becomes zero, and the servomotor stops. The angular position of magnet 13, when so adjusted, corresponds to the magnitude and direction of the control current.

To obtain easily read indications of the magnitude and direction of control current, I may attach to shaft 15 a pointer 24 and provide a scale 25 suitably calibrated in appropriate units. Alternatively, or in addition, I may connect shaft 15 to a recorder, or to any other mechanism which I may desire to actuate in accordance with control current values.

It will be understood that my invention is not limited to the specific embodiment herein illustrated and described, and that the following claims are intended to cover all changes and modifications which do not depart from the true spirit and scope of the invention.

What I claim as new and desire to secure by Letters Patent of the United States is:

1. A saturable magnetic core control device comprising a permanent magnet producing at least a portion of a magnetic flux termed the control flux, a signal winding, a magnetic core member having at least two saturable parts through which the control flux may pass, said permanent magnet being adjustable in position

relative to said core member for varying the magnitude and direction of its portion of the control flux, an excitation winding, and alternating current connections and a half-wave rectifier in series with said excitation winding for applying pulsating direct current thereto, said excitation winding being arranged to provide pulsating magnetic flux which in its relation to the control flux is simultaneously additive in one of said saturable parts and subtractive in the other, said signal winding being arranged in balanced relation to equal amounts of pulsating flux in said two saturable parts, whereby an induced alternating voltage signal occurs across said signal winding only as said parts are unequally saturated by action of the control flux.

2. A saturable magnetic core control device responsive to an electric current of variable magnitude and direction termed the control current, comprising a signal winding and connections for applying the control current thereto, thereby producing a portion of a magnetic flux termed the control flux, a permanent magnet producing another portion of the control flux, a magnetic core member having at least two saturable parts through which the control flux may pass, said permanent magnet being adjustable in position relative to said core member for varying the magnitude and direction of its portion of the control flux, an excitation winding, and alternating current connections and a half-wave rectifier in series with said excitation winding for applying pulsating direct current thereto, said excitation winding being arranged to provide pulsating magnetic flux which in its relation to the control flux is simultaneously additive in one of said saturable parts and subtractive in the other, said signal winding being arranged in balanced relation to equal amounts of pulsating flux in said two saturable parts, whereby an induced alternating voltage signal occurs across said signal winding only as said parts are unequally saturated by action of the control flux.

3. A saturable magnetic core control device responsive to a magnetic flux of variable magnitude and direction termed the control flux, comprising a magnetic core member having at least two saturable parts through which the control flux may pass, an excitation winding, alternating current connections and a half-wave rectifier in series with said excitation winding for applying pulsating direct current thereto, said excitation winding being arranged to provide pulsating magnetic flux which in its relation to the control flux is simultaneously additive in one of said saturable parts and subtractive in the other, a signal winding arranged in balanced relation to equal amounts of pulsating flux in said two saturable parts, whereby an induced alternating voltage signal occurs across said signal winding only as said parts are unequally saturated by action of the control flux, a servomotor having a field winding and a control winding, said servomotor being of a type which rotates in either direction selectively depending upon the phase relation between alternating currents supplied to said field winding and said control winding respectively, electrical connecting means to supply said field winding with alternating current which is substantially in phase quadrature with the fundamental-frequency alternating component of the pulsating current applied to said excitation winding, and electrical connecting means for transmitting fundamental-frequency signals from said signal winding to said control winding,

whereby operation of said servomotor is controlled by the control flux.

4. A saturable magnetic core control device responsive to an electric current of variable magnitude and direction termed the control current, comprising a signal winding and connections for applying the control current thereto, thereby producing a portion of a magnetic flux termed the control flux, a permanent magnet producing another portion of the control flux, a magnetic core member having at least two saturable parts through which the control flux may pass, said permanent magnet being adjustable in position relative to said core member for varying the magnitude and direction of its portion of the control flux, an excitation winding, alternating current connections and a half-wave rectifier in series with said excitation winding for applying pulsating direct current thereto, said excitation winding being arranged to provide pulsating magnetic flux which in its relation to the control flux is simultaneously additive in one of said saturable parts and subtractive in the other, a signal winding arranged in balanced relation to equal amounts of pulsating flux in said two saturable parts, whereby an induced alternating voltage signal occurs across said signal winding only as said parts are unequally saturated by action of the control flux, a servomotor having a field winding and a control winding, said servomotor being of a type which rotates in either direction selectively depending upon the phase relation between alternating currents supplied to said field winding and said control winding respectively, electrical connecting means to supply said field winding with alternating current which is substantially in phase quadrature with the fundamental frequency of the alternating components of the pulsating current applied to said excitation winding, electrical connecting means for transmitting fundamental frequency signals from said signal winding to said control winding, whereby operation of said servomotor is controlled by the control flux, and mechanical connections between said servomotor and said permanent magnet such that operation of said servomotor adjusts the position of said magnet to balance the two portions of control flux, whereby said magnet is adjusted automatically to positions which respectively correspond to unique values in magnitude and direction of the control current.

5. A saturable magnetic core control device responsive to an electric current of variable magnitude and direction termed the control current, comprising a signal winding and connections including a series reactor for applying the control current thereto, thereby producing a portion of a magnetic flux termed the control flux, a permanent magnet producing another portion of the control flux, a magnetic core member having at least two saturable parts through which the control flux may pass, said permanent magnet being adjustable in position relative to said core member for varying the magnitude and direction of its portion of the control flux, an excitation winding, alternating current connections and a half-wave rectifier in series with said excitation winding for applying pulsating direct current thereto, said excitation winding being arranged to provide pulsating magnetic flux which in its relation to the control flux is simultaneously additive in one of said saturable parts and subtractive in the other, said signal winding being arranged in balanced relation to equal amounts of

pulsating flux in said two saturable parts, whereby an induced alternating voltage signal occurs across said signal winding only as said parts are unequally saturated by action of the control flux, a servomotor having a field winding and a control winding, said servomotor being of a type which rotates in either direction selectively depending upon the phase relation between alternating currents supplied to said field winding and said control winding respectively, electrical connections including a series capacitor for supplying said field winding with alternating current which is substantially in phase quadrature with the fundamental-frequency alternating component of the pulsating current supplied to said excitation winding, a parallel resonant circuit connected in series with a direct-current blocking capacitor across said signal winding, said resonant circuit consisting of a reactor and a capacitor in parallel which are resonant to fundamental-frequency signals, electrical means connecting said control winding across said resonant circuit, whereby operation of said servomotor is controlled by the control flux, and mechanical connections between said servomotor and said permanent magnet such that operation of said servomotor adjusts the position of said magnet to balance the two portions of control flux, whereby said magnet is adjusted automatically to positions which respectively correspond to unique values in magnitude and direction of the control current.

6. A saturable magnetic core control device responsive to an electric current of variable magnitude and direction termed the control current, comprising a magnetic core member having two saturable outer legs and a center leg having a gap therein, an excitation winding, alternating current connections and a half-wave rectifier in series with said excitation winding for applying pulsating direct current thereto, said excitation winding consisting of two series-connected balanced halves so wound upon said two outer legs respectively that a pulsating magnetic flux passes in opposite directions through the two saturable outer legs, a signal winding and connections for

applying the control current thereto, thereby providing a portion of a magnetic flux termed the control flux, a transversely magnetized permanent magnet positioned within the gap of said center leg to provide another portion of the control flux, said permanent magnet being rotatable relative to said core member of varying the magnitude and direction of its portion of the control flux, said signal winding consisting of two series-connected balanced halves so wound upon said two legs respectively that the control flux passes in the same direction through the two saturable legs, whereby an induced alternating voltage signal occurs across the whole of said signal winding only as said legs are unequally saturated by action of the control flux, a servomotor having a field winding and a control winding, said servomotor being of a type which rotates in either direction selectively depending upon the phase relation between alternating current applied to said field winding and said control winding respectively, electrical connecting means to supply said field winding with alternating current which is substantially in phase quadrature with the fundamental-frequency alternating component of the pulsating current applied to said excitation winding, electrical connecting means for transmitting fundamental-frequency signals from said signal winding to said control winding, whereby operation of said servomotor is controlled by the control flux, and mechanical connections between said servomotor and said permanent magnet such that operation of said servomotor adjusts the position of said magnet to balance the two portions of control flux, whereby said magnet is adjusted automatically to positions which respectively correspond to unique values in magnitude and direction of the control current.
